The ornamental design for a slat wall memorial display unit, as shown and described.

DESCRIPTION

FIG. 1 is a front view of a slat wall memorial display unit; FIG. 2 is a side perspective view thereof, viewed from above;

FIG. 3 is an opposite side perspective view thereof, viewed from below;

FIG. 4 a side perspective view of FIG. 2, but showing a different arrangement of shelves;

FIG. 5 is a side perspective view of FIG. 2, but showing another arrangement of shelves;

FIG. 6 is a side perspective view from above of an additional embodiment of the slat wall memorial display unit; and, FIG. 7 is an opposite side perspective view of FIG. 6, viewed from below.

The broken line showing of shelves is for illustrative purposes only and forms no part of the claimed design.
